DESIGN FOR LACE CURTAIN

Hugo Geller, New York, N. Y., assignor to Patchogue-Plymouth Mills Corporation, New
York, N. Y., a corporation of New York

Application March 21, 1935, Serial No. 55,986

Term of patent 14 years

To all whom it may concern:

Be it known that I, Hugo Geller, a citizen of the United States, residing in the Borough of Manhattan, county of New York, and State of New York, have invented a new, original, and ornamental Design for Lace Curtain, of which the following is a specification, reference being had to the accompanying drawing, forming part thereof.

Fig. 1 is a plan view of a lace curtain showing my design; and Figs. 2 and 3 are vertical and horizontal sections taken respectively along lines 2—2 and 3—3 of Fig. 1.

What is claimed is:

The ornamental design for lace curtain as shown.

HUGO GELLER.
